COFFEE URN

Walter B. Law and Warren B. Law, Dunellen, N. J.

Application September 25, 1948, Serial No. 148,762

Term of patent 14 years

(Cl. D44—26)

To all whom it may concern:

Be it known that we, Walter B. Law and Warren B. Law, citizens of the United States, residing at Dunellen, in the county of Middlesex and State of New Jersey, have invented a new, original, and ornamental Design for Coffee-Urns, of which the following is a specification, reference being had to the accompanying drawing, forming part thereof.

The figure is a perspective view of a coffee-urn showing our new design, taken from the front thereof.

The urn is substantially circular in cross section and except for the absence of the draining device the opposite side is similar to that shown.

We claim:

The ornamental design for a coffee-urn, as shown and described.

WALTER B. LAW.
WARREN B. LAW.
